UNITED STATES PATENT OFFICE

168,643

TELEVISION CABINET

Samuel E. Adler, Chicago, Ill.

Application October 25, 1952, Serial No. 21,990

Term of patent 14 years

(Cl. D56—4)

To all whom it may concern:

Be it known that I, Samuel E. Adler, a citizen of the United States, residing at Chicago, in the county of Cook, State of Illinois, have invented a new, original, and ornamental Design for a Television Cabinet, of which the following is a specification, reference being had to the accompanying drawings, forming a part hereof.

Fig. 1 is a front elevational view of a television cabinet, the doors of which are closed, showing my new design;

Fig. 2 is a perspective view of the cabinet when the doors thereof are in open position;

Fig. 3 is a side elevational view of the cabinet, a portion thereof being broken away and exposing underlying parts;

Fig. 4 is a fragmentary sectional view on line 4—4 of Fig. 3; and

Fig. 5 is also a fragmentary sectional view taken on line 5—5 of Fig. 3.

The dominant features of my design reside in

those portions shown by full lines of the drawings.

I claim:

The ornamental design for a television cabinet, as shown and described.

SAMUEL E. ADLER.
